FUNGICIDES AND METHOD OF MAKING SAME

Stanley B. Elliot, Walton Hills, and Albright M. Nicholson, Cleveland, Ohio, assignors to Ferro Chemical Corporation, Bedford, Ohio, a corporation of Ohio

No Drawing. Application February 28, 1955,
Serial No. 491,174

12 Claims. (Cl. 260—270)

This invention relates as indicated to compositions having fungicidal and/or fungistatic properties and has more particular reference to a process for solubilizing such compositions.

During the past decade considerable research has been conducted for the purpose of finding new and improved fungicidal compositions. It is well known that the hydroxyquinolines have good fungicidal and/or fungistatic properties, however, they are all substantially insoluble in the common industrial solvents and therefore have encountered considerable difficulties in commercial applications. Due to their substantial insolubility these aforementioned materials have poor resistance to "cracking" and "leaching" and lose their effectiveness due to poor penetration of the material being treated.

It is therefore a principal object of our invention to provide a method and means for rendering the hydroxyquinolines soluble in the common industrial solvents, such as, V. M. & P. naphtha, mineral spirits, fuel oil, etc.

Other objects will become apparent as the description proceeds.

To the accomplishment of the foregoing and related ends, the invention, then, comprises the features herein-after fully described and particularly pointed out in the claims, the following description setting forth in detail certain illustrative embodiments of the invention, these being indicative, however, of but a few of the various ways in which the principle of the invention may be employed.

Broadly stated this invention then comprises the method of solubilizing the hydroxyquinolines which consist in heating a hydroxyquinoline together with a water insoluble metal carboxylic acid soap and an alkyl phenol in which the alkyl group has at least 8 and not more than 15 carbon atoms.

The alkyl radicals of the alkyl phenols, used as reactants in the present invention, may be normal or branched. In the case of dialkyl compounds the two alkyl radicals are not necessarily similar. We have found the following alkyl phenols to be particularly useful in the process of our invention:

Octyl phenol
Nonyl phenol
Dodecyl phenol
Penta-decyl phenol

The metal soaps which are used as reactants in the present invention are the water insoluble soaps. Thus they may be soaps of any metal or mixture of metals which form water insoluble soaps with soap-forming acids or mixtures of such acids. In the preferred embodiment of our invention we use the copper, zinc and nickel soaps. However, it will be noted that aluminum, magnesium and the alkaline earth metals are also usable in the invention.

The soap-forming acids used in forming the aforementioned metal soaps include stearic, palmitic, lauric, 2-ethylhexoic, linoleic, linolenic, oleic, ricinoleic and naphthenic and mixtures thereof. Soap-forming fatty acids such as tall oil, rosin oil, rosin and abietic may also be used in making the water-insoluble soaps. In the preferred em-

bodiment of our invention we use those saturated and unsaturated aliphatic acids having from 8-18 carbon atoms.

As previously stated the hydroxyquinolines are substantially insoluble in the common organic solvents. The reaction products of the present invention, on the other hand, are readily soluble in toluene, mineral spirits, naphtha, fuel oil, etc. and the resultant solutions have very effective fungicidal properties.

10 While the hydroxyquinolines in general have effective fungicidal properties we prefer the use of 8-hydroxyquinoline.

In carrying out the process of the present invention the reactants should be heated to a temperature in the range of about 200° F. to the lowest decomposition temperature of the components, with good agitation. From 5% to above 20% of hydroxyquinoline can be put into solution in this process using the above components.

15 The following examples are illustrative of a few ways of preparing the reaction products of the present invention.

I

158 lbs. of copper naphthenate were heated with 51 lbs. of pentadecyl phenol and 27.5 lbs of 8-hydroxyquinoline 25 in an open vessel, with constant agitation, to 375° F. The temperature was held for about 15 minutes. The solution was then allowed to cool to about 220° F. and was then diluted with 82.5 lbs. of mineral spirits.

The resulting solution was brilliant, clear and substantially free of undissolved matter when observed by the eye under a light.

30 The reaction products of the present invention vary at room temperature from free flowing masses to solids. However, all are readily soluble and may be diluted with 35 any of the common solvents such as mineral spirits. Generally the reaction products of the present invention can be diluted with the common organic solvents at room temperature, however, we have found that the use of heat will facilitate dispersion.

35 The products of the present invention may be applied in the material to be treated by dipping, spraying or by being incorporated into a still more complex composition and "knifed" onto the material. The aforementioned complex compositions may be of a wide variety of resins 40 and waterproofing agents.

II

200 lbs. of nickel 2-ethyl hexoate were heated with 102 lbs. of nonyl phenol and 55 lbs. of 8-hydroxyquinoline in 50 an open vessel, with constant agitation, to about 325° F. The temperature was held for about 20 minutes and allowed to cool to about 175° F. and was then diluted with 280 lbs. of mineral spirits.

The resultant produce was clear when viewed with the eye under light.

55 The reaction products of the present invention may be used as fungicidal and/or fungistatic compositions in the hot liquefied state or in the solidified state or as hot or cold solutions in the common organic solvents.

III

310 lbs. of zinc naphthenate were heated with 102 lbs. of dodecyl phenol and 55 lbs. of 8-hydroxyquinoline in 60 an open vessel with stirring and the temperature was raised to about 325° F. held for about 25 minutes. The mass was allowed to cool to about 175° F. and was then diluted with 170 lbs. of mineral spirits.

IV

70 200 lbs. of copper 2-ethyl hexoate were heated with 102 lbs. of octyl phenol and 55 lbs. of 8-hydroxyquinoline in an open vessel with constant stirring. The tempera-

ture was raised to about 350° F. and held for about 15 minutes. The mass was allowed to cool to about 225° F. and was then diluted with 280 lbs. of mineral spirits.

The resultant product showed exceptionally good clarity and substantially no undissolved matter when viewed under light.

245 lbs. of copper 2-ethyl butoxy propionate were heated with 102 lbs. of dodecyl phenol and 55 lbs. of 8-hydroxyquinoline in an open vessel with constant agitation. The temperature was raised to about 315° F. and held for about 15 minutes. The mass was allowed to cool to about 225° F. and was then diluted with 235 lbs. of mineral spirits.

130 lbs. of nickel 2-ethyl hexoate were heated with 70 lbs. of copper 2-ethyl hexoate, 102 lbs. of pentadecyl phenol and 55 lbs. of 8-hydroxyquinoline in an open vessel with stirring. The temperature was raised to about 350° F. and held for about 20 minutes. The mass was allowed to cool to about 200° F. and was then diluted with 280 lbs. of mineral spirits.

The resultant product showed excellent clarity and excellent fungicidal properties.

Additional reaction products of the present invention were made and tested to determine their efficacy as fungicides. Solutions of each were used to impregnate samples of duck and they showed results substantially identical with the foregoing examples.

Tests were carried out on the products of the present invention to determine their efficacy as fungicides. Tests were as follows:

Samples of 10 oz. duck were cut 1 1/4" x 6" and the width was ravelled to 1". Half of the samples were cut parallel to the filling threads. Untreated specimens were always included in the tests as controls to verify the viability of the test organisms.

The samples to be treated were dipped into a solution of one of the products of the present invention. As for example, the reaction product of Example I was diluted to 18.5% with mineral spirits and the textiles were dipped into this solution for 1 minute. The treated textiles were then put through a wringer and adjusted to 65% pick up of the fungicide on a dry weight basis and then they were allowed to air dry to constant weight. One-half of the treated samples were placed directly in the fungus growth and the other half were thoroughly leached in water and dried before being subjected to the fungus growth.

Spore suspensions of *chaetomium globosum* and *aspergillus niger* were introduced onto an agar culture medium contained in a sterile bottle and then incubated for 48 hours at 84° ± 2° F. at 90-95% relative humidity. At the end of the 48 hour incubation period the treated samples (leached and unleached) and the untreated samples were dipped in distilled water and then pressed firmly on the surface of the inoculated culture medium to insure good contact. After 14 days the samples were observed visually and subjected to breaking tests.

At the end of 14 days all untreated samples were completely covered with fungi growth and were reduced in tensile strength by 50% or more. The treated samples both leached and unleached showed no fungus growth and substantially no loss in tensile strength. There was no difference in appearance between the leached and unleached treated samples, however, the leached samples showed a slightly higher tensile strength than did the unleached samples.

The products of the present invention are stable for long periods of time and not only inhibit the growth of fungi but also kill the activity of existing growth on contact.

- 5 Other modes of applying the principle of the invention may be employed, change being made as regards the details described, provided the features stated in any of the following claims or the equivalent of such be employed.
- 10 We, therefore, particularly point out and distinctly claim as our invention:
1. The method of producing a composition of matter which consists of reacting at temperatures between 200° F. and the lowest decomposition temperature of the reactants, 15 hydroxyquinoline, with at least one water insoluble metal organic acid soap, said metal soap selected from the group consisting of the metal water insoluble soaps of stearic, palmitic, lauric, 2-ethyl-hexoic, linoleic, linolenic, oleic, ricinoleic, naphthenic, tall oil, rosin oil, rosin and abietic acids and an alkyl phenol in which the alkyl group has at least 8 and not more than 15 carbon atoms.
  2. The method of producing a composition of matter which consists of reacting at temperatures between 200° F. and the lowest decomposition temperature of the reactants, 25 8-hydroxyquinoline, with at least one water insoluble metal organic acid soap, said metal soap selected from the group consisting of the metal water insoluble soaps of stearic, palmitic, lauric, 2-ethyl-hexoic, linoleic, linolenic, oleic, ricinoleic, naphthenic, tall oil, rosin oil, rosin and abietic acids and an alkyl phenol in which the alkyl group has at least 8 and not more than 15 carbon atoms.
  3. A method of producing a composition of matter which consists of reacting at temperatures between 200° F. and the lowest decomposition temperature of the reactants, 35 8-hydroxyquinoline, copper naphthenate and pentadecyl phenol.
  4. A method of producing a composition of matter which consists of reacting at temperatures between 200° F. and the lowest decomposition temperature of the reactants, 40 8-hydroxyquinoline, copper laurate and pentadecyl phenol.
  5. A method of producing a composition of matter which consists of reacting at temperatures between 200° F. and the lowest decomposition temperature of the reactants, 45 8-hydroxyquinoline, nickel 2-ethyl hexoate and pentadecyl phenol.
  6. A method of producing a composition of matter which consists of reacting at temperatures between 200° F. and the lowest decomposition temperature of the reactants, 50 8-hydroxyquinoline, zinc laurate and pentadecyl phenol.
  7. As a new composition of matter the product produced by claim 1.
  8. As a new composition of matter the product 55 produced by claim 2.
  9. As a new composition of matter the product produced by claim 3.
  10. As a new composition of matter the product produced by claim 4.
  - 60 11. As a new composition of matter the product produced by claim 5.
  12. As a new composition of matter the product produced by claim 6.
